UNITED STATES PATENT OFFICE.

WILLIAM J. TATRO, OF BROCKTON, MASSACHUSETTS, ASSIGNOR TO UNITED SHOE MACHINERY COMPANY, OF PATERSON, NEW JERSEY, A CORPORATION OF NEW JERSEY.

EYELET-SETTING TOOL.

1,184,592.

Specification of Letters Patent. Patented May 23, 1916.

Application filed September 22, 1914. Serial No. 862,920.

To all whom it may concern:

Be it known that I, WILLIAM J. TATRO, a citizen of the United States, residing at Brockton, in the county of Plymouth and State of Massachusetts, have invented certain Improvements in Eyelet-Setting Tools, of which the following description, in connection with the accompanying drawings, is a specification, like reference characters 10 on the drawings indicating like parts in the several figures.

The present invention relates to tools for setting blind or invisible eyelets in sheet material such, for example, as the uppers 15 of boots and shoes.

It has been the practice to employ in power eyeleting machines a tool having an outwardly projecting shoulder of relatively small diameter upon which the upsetting 20 surface is formed, the construction being such that the upsetting surface may be passed through the outer part of the shoe upper and located substantially between the outer and lining parts.

One object of the present invention is to provide for such a tool means for holding the work in a flat condition adjacent to the eyelet being set and for yieldingly opposing the thrust imparted to it by the eyelet as the latter is inserted from the opposite side of the work. This is important because otherwise the advancing end of the eyelet barrel would push the material of the work ahead of it and force the lining upon the tool so far that the eyelet barrel would be clenched without passing through the lining. This is particularly the case in dealing with light material which stretches readily as it is forced upon the upsetting tool.

As herein shown the desired results are attained by arranging upon the upsetting tool a washer of rubber or other resilient material with its work engaging surface disposed in the vicinity of the upsetting 45 surface of the tool.

In addition to the functions above mentioned a device of this character acts also as a stripper tending to press the work toward the end of the setting tool after the 50 setting pressure has been released. This facilitates the operation at a high speed of an eyeleting machine equipped with the setting tool in that it reduces the interval during which the tool projects into the work.

The construction and manner of using the

novel tool of this invention will be best understood and appreciated from the following description of a preferred embodiment thereof selected for purposes of illustration and shown in the accompanying drawings 60 in which,—

Figure 1 is a view in side elevation of the upsetting tool; Fig. 2 is a sectional view of the coöperating setting tools showing their positions in a shoe upper at the completion of the setting operation.

As shown in Fig. 1 the upsetting tool comprises a cylindrical body portion 10 shouldered at its lower end and provided with a concentric projecting portion 12. 70 The portion 12 is, in turn shouldered to form the curved upsetting surface 14 against which the end of the eyelet barrel is clenched in the setting operation. Below the upsetting surface 14 is a portion 16 of the tool which is tapered somewhat toward the end of the tool. In the embodiment of the invention herein shown the upsetting tool is utilized also as a punch and accordingly the tool is provided with a central 80 longitudinal bore and the lower edge of the portion 16 is shaped for punching. In case it is desired to use the tool in a machine equipped with separate punching mechanism, the upsetting tool may be solid and its 85 end shaped to enter the punched hole and to pass through both parts of the work. Surrounding the portion 12 and held thereon by friction is a washer 18 of leather, rubber or other suitable resilient material. The 90 upper surface of the washer 18 bears against the lower surface of the body portion 10 of the tool while the lower or work engaging surface of the washer is disposed above the upsetting surface 14 by a distance somewhat less than the thickness of the uppermost layer of the two layers of material in which the blind or invisible eyelets are to be set.

The upsetting tool is intended to be used 100 in coöperation with an eyelet carrying or inserting set of the usual construction, such a set being indicated by reference character 20 in Fig. 2. This tool is shaped at its upper end to receive the flange of the eyelet 105 and provided with a center spindle 21 which holds the eyelet in place preliminarily to the setting operation and then yields downwardly into the set 20 when it encounters 110 the upsetting tool.

The outer or leather part 22 of an upper is also shown in Fig. 2 and the lining portion is shown as comprising a layer 24, which may be the facing stay or leather lining part, and a stiffening strip 25 which is commonly provided to afford better holding for the eyelets.

In using the tools above described the end of the upsetting tool is passed substantially through both parts of the work cutting out its own hole as it advances. Although the hole formed by the upsetting tool is of less diameter than the portions of the tool immediately above the punching end thereof the material of the upper will stretch sufficiently to permit the outer part 22 of the upper to be crowded over the upsetting shoulder 14 upon the portion 12 of the tool. An eyelet is supplied to the set 20 and, with the two tools arranged in alinement, the set 20 is elevated to insert the eyelet barrel through the lining portions 24 and 25 of the upper. In this operation the set 20 and the eyelet carried thereby tend to force the work upwardly upon the upsetting tool and, if this movement were not opposed, the lining portions 24 and 25 might also be crowded above the upsetting shoulder 14 so that the eyelet would be clenched below the lining portion. It might happen also that the material on one side of the tool would be crowded upwardly past the upsetting shoulder and in this case part of the eyelet barrel would be clenched properly above the lining and the remainder would be clenched within or below the lining. As above intimated the provision of the resilient washer 18 obviates such difficulties for the washer engages the outer portion 22 of the upper over a considerable area adjacent to the upsetting surface and holds this portion in a flat condition and consequently the lining portions 24 and 25 will also be held in a flat condition. Moreover the washer yieldingly opposes the upward movement of the work upon the upsetting tool and so insures that the end of the eyelet barrel shall pass through the lining and not merely push the work ahead of it. In eyeleting work of different thicknesses it is contemplated that washers of the appropriate dimensions will be placed in position upon the upsetting tool.

Having thus described my invention, I claim as new and desire to secure by Letters Patent of the United States:

1. A tool for setting blind or invisible eyelets, having a body portion terminating in a rigid shoulder, a portion projecting therefrom and being provided with an outwardly extending upsetting shoulder, and a washer of resilient material surrounding the projecting portion and having its work

engaging surface located adjacent to the upsetting shoulder.

2. A tool for setting blind or invisible eyelets, having its end shaped to pass through both the lining and the outer parts of an upper, a concentric upsetting shoulder of small diameter located above the end of the tool so that it may be carried through one part of the upper, a washer of resilient material located mainly above the upsetting shoulder, and a washer supporting surface formed by part of the tool.

3. A tool for setting blind or invisible eyelets, having an outwardly extending shoulder shaped to constitute an upsetting surface, and a rubber washer so located as to act as a stripper tending to push the work from the upsetting surface after the clenching operation.

4. A tool for setting blind or invisible eyelets, having an upsetting shoulder of relatively small diameter constructed and arranged to be carried substantially through one part of an upper, and a resilient member having substantially greater width than thickness and being carried by the tool itself to oppose yieldingly the movement of the said part of upper upon the tool.

5. A tool for setting blind or invisible eyelets, having a reduced end formed as a tubular punch, a shoulder disposed above the end of the tool and having an outwardly and upwardly curved upsetting shoulder of relatively small exterior diameter so that it may be forced through the hole formed by the punching end of the tool in the upper of two superposed layers of sheet material, and a work engaging device perforated to fit upon the tool above the upsetting shoulder and having a lower work engaging face which is normally disposed above the upsetting shoulder and is capable of adjustment to accommodate material of different thicknesses.

6. A tool for setting blind or invisible eyelets, comprising a body portion terminating in a shoulder, a portion of reduced diameter projecting from said shoulder and having formed therein an upsetting shoulder, whereby said reduced portion and upsetting shoulder may be passed through one part of a shoe upper, and a washer of resilient material having a work engaging surface disposed normally above the periphery of the upsetting shoulder.

In testimony whereof I have signed my name to this specification in the presence of two subscribing witnesses.

WILLIAM J. TATRO.
